UNITED STATES PATENT OFFICE

HOWARD T. CASEY, OF BALTIMORE, MARYLAND, ASSIGNOR TO T. H. SYMINGTON & SON, INC., OF BALTIMORE, MARYLAND, A CORPORATION OF MARYLAND

SWING HANGER FOR RAILWAY TRUCKS

Application filed October 13, 1930. Serial No. 488,499.

The invention relates to railway car trucks and has special reference to that type in which the spring plank carrying the springs which support the bolster is itself mounted on hangers pivoted to the transoms, this being the type of construction used in six wheel trucks for passenger cars.

It is well known that in ordinary practice the hangers are so constructed that the truck bolster may move laterally freely as is desirable when rounding curves. Furthermore as the movement of the fulcrum points beneath the spring plank is in an arc of a circle there is a lifting effect exerted on the bolster which is supposed to counteract or neutralize the centrifugal force developed when the car passes over curved track, which force is what moves the bolster laterally. The hangers are ordinarily quite long and when depended in parallel relation they give excellent riding qualities to a passenger car travelling on straight track. However, upon striking a curve the above referred to lift or arc of rise is insufficient to absorb the centrifugal force developed upon lateral motion of the bolster and consequently a distinct shock results. One attempted method of overcoming this difficulty would be to shorten the hangers so that the arc of rise will be more abrupt for the purpose of increasing the resistance to the centrifugal force. The difficulty then is that the normal floating movement is insufficient when the car is travelling on straight track and the riding qualities are impaired.

It is with all of the above facts in view that I have devised the present invention which has for its general object the provision of a novel hanger construction in which there will be the same floating action or freedom of movement of the bolster under normal or straight track conditions combined with a more abrupt rise of the fulcrum points for the spring plank, or more abrupt lifting of the bolster when the lateral motion thereof exceeds a predetermined degree so that the centrifugal force will be entirely absorbed and without there being any shock or jar of any kind whatsoever.

An important object of the invention is to

provide a suspension hanger embodying relatively movable parts and which under straight track conditions operates in the same manner as an integral hanger, the parts having, however, relative movement when the car travels over curved track, the relative movability providing the means for developing the more abrupt arc of rise.

Another important object is to provide a hanger of this character which may be used to replace the ordinary hanger without any changes in the construction of the truck other than the provision of a pair of stops to coact with one of the relatively movable sections or parts of each hanger.

Another object is to provide a hanger construction of this character which may be applied or installed with as much ease as one of the ordinary type.

An additional object is to provide a hanger construction which will be simple, inexpensive to manufacture, positive in action, efficient and durable in service, and a general improvement in the art.

To the attainment of the foregoing and other objects and advantages, the invention preferably consists in the details of construction and the arrangement and combination of parts to be hereinafter more fully described and claimed, and illustrated in the accompanying drawing in which:

Figure 1 is a fragmentary cross section through one side of a passenger car truck showing my novel hanger installed, and

Figure 2 is a section taken on substantially the line 2-2 of Figure 1.

Referring more particularly to the drawing the numeral 10 designates the usual transom construction here represented as forming an integral part of the side frame and 11 represents the truck bolster which of course extends across between the transoms with its ends projecting therebeyond in the ordinary manner. The bolster is supported by the springs 12 here disclosed as of the elliptic type and which in turn rest upon the spring plank 13 beneath each end of which is a bearing member 14 carried by a fulcrum element 15 mounted in a hanger device to be described. The ordinary hanger is of sub-

stantially U-shape with the bearing element 15 mounted in its bight and has its upper ends pivoted on the transom at the top thereof.

In carrying out the present invention I 5 replace the ordinary type or one piece hanger with a sectional or two-part hanger indicated as a whole by the numeral 16 which is, however, mounted in the same manner. This hanger 16 may of course be of any desired 10 detailed construction but is here shown as comprising a U-shaped lower member 17 including a bight portion 18 and upstanding arms bifurcated at 19 to provide pairs of 15 spaced ears 20. The lower ends of a pair of links 21 are received within the bifurcations 19 and are pivoted to the lower member 17 as by pins or the like 22 which may be prevented from longitudinal displacement by 20 any suitable means, such as cotters or the like 23. At their upper ends the links 21 are 25 preferably enlarged to form bosses 24 through which extends a supporting shaft, bolt or pin 25 which has its ends projecting beyond the bosses and engaged upon seats 26 formed in the top surface of the transom. These seats operate to prevent longitudinal as well as lateral displacement of the member 25.

It is of course apparent that the lower 30 member 17 of the hanger is capable of movement with respect to the links 21 though it is not desired that this movement take place until the bolster 11 has moved laterally to a certain predetermined extent. To insure 35 proper action I have shown the transom as provided at opposite sides with pairs of spaced stops 27 which may be integral with the transom if preferred but which can of course be formed as separate parts secured thereto if such should be desired for any reason, for example when installing my hanger in an already existing truck. The space between the confronting faces of each pair of 40 stops 27 is somewhat greater than the width 45 of the links 21 so that the links 21 and lower member 17 of the hanger may have swinging movement through a certain arc while remaining in alinement, the lower member 17 of course pivoting on the members 22 when 50 the links 21 engage against one set or other of the stops, the lower member 17 then swinging in an arc of much less diameter.

In the operation of a truck embodying my 55 novel hanger construction it will be seen that as these hangers may conform to the standard length there will be the same freedom of movement or floating action of the bolster when the car is travelling along straight track as under such circumstances the links 60 21 do not engage the stops 27, thereby permitting the fulcrum members 15 to swing in the usual arc concentric with the axis of the shaft or pin 25. The great advantage is that when the car travels over curved track 65 the centrifugal force developed moves the

bolster to such an extent that the links 21 strike against the stops 27, their movement beyond this certain predetermined point being thus checked. When this occurs the lower member 17 of the hanger continues to move but the arc on which the fulcrum elements 15 then swing is much more abrupt as it is concentric with the members 22. This naturally produces a sudden rise and the increased lifting action exerted against the bolster and the load thereon will counteract or absorb the centrifugal force so that there will be a total absence of any shock or jar at any point in the truck structure, thereby insuring the highly desirable easy riding qualities of the car. Attention is directed to the fact that the hanger is of remarkably simple construction, that it is rugged and durable and that it may not only be installed as easily as the ordinary variety but may be assembled in an already existing truck without necessitating any changes in the construction thereof other than providing stops for coaction with the upper sections or links of the hangers. It is thought from the foregoing that the construction, operation and advantages should be readily apparent to one skilled in the art without further explanation.

While I have shown and described the preferred embodiment of the invention, it should be understood that the disclosure is merely an exemplification of the principles involved as the right is reserved to make all such changes in the details of construction as will widen the field of utility and increase the adaptability of the device provided such changes constitute no departure from the spirit of the invention or the scope of the claims hereunto appended.

Having thus described the invention, I claim:

1. In a lateral motion truck including transoms and a suspended bolster movable laterally thereof, supporting means for the bolster comprising a plurality of connected parts movable as a whole for the first portion of their travel and relatively movable for the remainder of their travel.

2. In a railway car truck including a lateral motion bolster, supporting means for the bolster comprising hangers pivotally depending from the truck and including sections swingable together about one axis during the first portion of their travel and relatively movable for the remainder of their travel.

3. In a railway car truck including transoms and a bolster movable laterally thereof, suspension means for the bolster comprising hangers pivoted with respect to the transoms and including pivotally connected parts, the hangers being swingable as a whole during the first portion of their travel and the parts thereof being relatively swingable during the remainder of their travel.

4. In a railway car truck including transoms, a bolster, means for swingably supporting the bolster comprising a spring plank, springs on the spring plank engaging the bolster, and hangers suspended from the transoms at their upper ends and having a fulcrum connection with the spring plank, said hangers including relatively movable parts.

10 5. In a railway car truck, transoms, a bolster movable laterally thereof, and suspension means for the bolster comprising hangers pivotally suspended from the transoms and including pivotally connected sections swingable as a whole during a portion of their travel, and means for holding certain sections of the hangers stationary after predetermined travel of the hangers as a whole.

20 6. In a railway car truck, transoms, a bolster movable laterally with respect thereto, and supporting means for the bolster comprising hangers pivotally suspended from the transoms and including upper and lower sections pivotally connected, said sections being swingable as a whole and in substantial alinement during a portion of their travel, and means cooperating with the upper sections for limiting the swinging movement thereof.

25 7. In a railway car truck, transoms, a bolster movable laterally with respect thereto, and supporting means for the bolster comprising hangers pivotally suspended from the transoms and including upper and lower sections pivotally connected, said sections being swingable as a whole and in substantial alinement during a portion of their travel, and means cooperating with the upper sections for limiting the swinging movement thereof while permitting continued swinging movement of the lower sections with respect to the upper sections.

30 8. In a railway car truck, transoms, a bolster movable laterally with respect thereto, and supporting means for the bolster comprising hangers pivotally suspended from the transoms and including upper and lower sections pivotally connected, said sections being swingable as a whole and in substantial alinement during a portion of their travel, and means cooperating with the upper sections for limiting the swinging movement thereof while permitting continued swinging movement of the lower sections with respect to the upper sections, said means comprising pairs of spaced stops on the transoms spaced apart a distance greater than the width of the upper sections.

35 9. In a railway car truck, transoms, a bolster movable laterally with respect thereto, and supporting means for the bolster comprising hangers pivotally suspended from the transoms and including upper and lower sections pivotally connected, said sections being swingable as a whole and in substantial

alinement during a portion of their travel, the initial movement being free and imparting gradual lift to the truck bolster, and means cooperating with the upper sections for limiting the swinging movement thereof and causing the lower sections to swing on a more abrupt tangential angle, thereby causing the bolster to lift by relatively larger increments, thus giving it the ability to absorb great energy at the end of the swing of the lower element.

In testimony whereof I affix my signature.

HOWARD T. CASEY.
